UNITED STATES PATENT OFFICE.

WILLIAM M. HINDS, SR., OF ATLANTA, GEORGIA.

AUXILIARY JAWS FOR WRENCHES.

Application filed March 31, 1925. Serial No. 19,713.

My invention relates, particularly, to auxiliary jaws readily applicable to the jaws of pipe wrenches for converting the latter into square head wrenches, but in general, my invention relates to auxiliary jaws adapted to protect and prevent excessive wear on the wrench jaws.

In the drawings:

Fig. 1 is a side view of a pipe wrench of usual construction, equipped with the auxiliary jaws according to the present invention.

Fig. 2 is a front view of the ensemble, according to Fig. 1, that is, as seen from the left of that figure.

Fig. 3 is a perspective of the upper auxiliary jaw.

Fig. 4 is a perspective of the lower auxiliary jaw.

Fig. 5 is a central vertical longitudinal section of Fig. 3, showing a modified form of a working face.

Fig. 6 is a central vertical longitudinal section of Fig. 4, showing the modified form of working face as in Fig. 5.

The wrench illustrated in Figures 1 and 2, is the well known Stillson wrench and will require no specific description.

Referring to Fig. 3 which shows the upper auxiliary jaw member, it will be seen that the latter consists essentially of a channel section having side walls 10 adapted to register with the side faces of the upper jaw of the wrench. These side walls are spaced from each other so as to fit closely against the side faces of the wrench head, as shown, particularly, in Fig. 2. The inner bottom surface 11 of the channel member is provided with serrations 12 adapted to engage, upon applying the auxiliary jaw member, with similar serrations upon the working face of the wrench head. A leaf spring 13 is set in a groove 14 in the outer surface of one of the walls 10 and is secured thereon near its lower end by means of a rivet 15. The upper end 13' of spring 13 extends over the top of wall 10 and projects beyond the inner edge of the latter.

The auxiliary jaw for the lower jaw of the wrench consists of a channel member having side walls 16 whose lower edges, when positioned, coincide substantially with shoulders 17 on the lower jaw of the wrench. The top wall of this channel member is provided on its

lower surface 18 with serrations 19, adapted to engage with the serrations on the working face of the lower jaw. A leaf spring 20 is secured in an oblique slot 16' in one of the walls 16 by means of a rivet 21, and an angular portion 20' of the spring 20 projects 60 inwardly beyond the wall 16.

From the above description and the drawings, it will be obvious that the hook ends of the springs are retractile, that is, upon pressure being applied to the ends thereof, the latter may be withdrawn completely from the channels of the auxiliary jaws. In applying the auxiliary jaws, therefore, ends 13' and 20' are retracted, whereupon the channel members may be seated in position by movements directly toward their respective jaws.

In the embodiment of my invention, illustrated in Figs. 1 to 4, the working faces of the channel members are plane surfaces, so that the wrench is converted into a square head wrench. For handling nickel pipe, however, I prefer to give the working face the arcuate configuration, shown in Figs. 5 and 6.

From the above it will be seen that I have provided auxiliary jaws of an extremely practical nature, due to their simplicity of structure and ease of attachment and removal, and while I have described a particular embodiment of my invention, it is to be understood that I do not limit myself as to structure except as determined in the following claims.

I claim:

1. In combination with a wrench having jaws with serrated gripping surfaces, auxiliary jaws comprising channel members adapted to slip over said jaws, said channel members having serrated bottom surfaces adapted to engage with said serrated gripping surfaces, the side walls of said channel members being spaced to fit closely the side faces of said jaws, and a leaf spring on a side wall of each of said jaws and having a hook portion extending inwardly beyond the side wall, said hook portions being retractile for permitting the application of the auxiliary jaws by movements directly toward their respective jaw faces.

2. Structure according to claim 1, wherein the leaf springs are set in slots in the side walls.

WM. M. HINDS, SR.
